TOGGLE SWITCH OPERATING DEVICE

Stuart J. Roberts, Denville, N.J.; Harold Rosenbaum, 29 Brittany Road, Montville, N.J. 07045; and Sol Inspector, 59 Fairfield Ave., West Caldwell, N.J. 07006; said Roberts assignor to said Rosenbaum and said Inspector

Filed Aug. 27, 1973, Ser. No. 391,776

Term of patent 14 years

Int. Cl. D8—09
U.S. Cl. D8—183

FIG. 1 is a front elevation of a toggle switch operating device showing our new design in a first mode of operation;

FIG. 2 is a front elevation of the device in a second mode of operation;

FIG. 3 is a rear elevation of the device as seen in the second mode of operation;

FIG. 4 is a left side elevation as seen in the second mode of operation;

FIG. 5 is a right side elevation as seen in the second mode of operation;

FIG. 6 is a bottom view of the device; and

FIG. 7 is a top view of the device.

We claim:

The ornamental design for a toggle switch operating device, substantially as shown and described.
